(57) **CLAIM**

The ornamental design for an LED lamp, as shown and described.

DESCRIPTION

FIG. 1 is a perspective view of a LED lamp showing our new design;

FIG. 1A is an enlarged view of the portion of FIG. 1 shown in the view circle 1A of FIG. 1;

FIG. 2 is a top view thereof, a bottom view being a mirror image thereof;

FIG. 3 is a front view thereof;

FIG. 3A is an enlarged view of the portion of FIG. 1 shown in the view circle 3A of FIG. 3;

FIG. 4 is a rear view thereof;

FIG. 4A is an enlarged view of the portion of FIG. 4 shown in the view circle 4A of FIG. 4;

FIG. 4B is an enlarged back perspective view of the portion of FIG. 4 shown in the view circle 4A of FIG. 4;

FIG. 5 is a right side view thereof, a left side view being a mirror image thereof; and,

FIG. 6 is an enlarged cross-sectional view thereof taken along the line VI—VI in FIG. 3.

FIG. 1 is a perspective view of an LED lamp showing our new design, with connector members being attached on either end thereof, the connector members being shown in broken lines and forming no part of the claimed design.
